ADJUSTABLE GAS PRESSURE REGULATOR

George L. Hammon, Oakland, Calif., assignor to Chemetron Corporation, Chicago, Ill., a corporation of Delaware

Filed Apr. 26, 1968, Ser. No. 11,638

Term of patent 14 years

Int. Cl. D23—01

U.S. Cl. D23—21

FIG. 1

FIG. 2

FIG. 3

FIG. 4

FIG. 5

FIG. 1 is a perspective view of an adjustable gas pressure regulator, illustrating my new design;

FIG. 2 is a front elevational view of the same;

FIG. 3 is a side elevational view of the same;

FIG. 4 is a rear elevational view of the same; and

FIG. 5 is an elevational view taken from the side opposite that shown in FIG. 3.

The broken line representations of pressure gauges and connectors in FIGS. 3 and 4 are for purposes of illustration only.

I claim:

The ornamental design for an adjustable gas pressure regulator, as shown and described.
